UNITED STATES PATENT OFFICE

2,141,329

VISCOSITY CUP

Erwin A. Zahn, Scotia, N. Y., assignor to General
Electric Company, a corporation of New York

Application December 16, 1936, Serial No. 116,144

2 Claims. (Cl. 265—11)

My invention relates to arrangements and apparatus for measuring viscosity and has for its principal object the provision of a simplified, inexpensive arrangement for quickly and accurately measuring viscosity free from temperature errors.

It is an object of my invention to provide an arrangement which permits easily and quickly obtaining a temperature-viscosity curve.

A further object of my invention is to provide a viscosity-measuring arrangement suitable for paints and oils as well as other liquids.

Other and further objects and advantages will become apparent as the description proceeds.

A better understanding of my invention may be obtained from the following detailed description when considered in connection with the accompanying drawing and those features of the invention which are believed to be novel and patentable will be pointed out in the claims appended hereto. In the drawing, Fig. 1 is a view partially in cross section of one embodiment of my invention and Fig. 2 is a detailed view partially in section of the viscosity cup utilized in the apparatus of Fig. 1. Like reference characters are utilized throughout the drawing to designate like parts.

In the form of the invention illustrated in the drawing, I provide a viscosity cup 11 spun or otherwise formed from a suitable material, such as sheet metal, and having an orifice 12 in the bottom thereof, the cup 11 being made bullet-shaped with a rounded nose 13 at the bottom end. For the purpose of suspending the cup 11 in the liquid 14, the viscosity of which is to be determined, a long handle 15 is provided which may consist of a wire loop fastened at the lower ends 16 to the sides of the cup 11 in any suitable manner as by welding or brazing. It will be understood that the lower ends 16 and the weld metal or hard solder 17 are preferably rounded and smoothed to avoid sharp edges or rough portions in order to minimize the production of turbulence when the cup is withdrawn from the liquid 14.

In order to eliminate temperature error, the cup 11 is kept constantly immersed in the liquid 14 and a suitable support, such as a pin or a hook 20 engaging a ring 21 loosely inserted in the top of the handle 15, is provided for supporting the viscosity cup 11 in the liquid 14. The arrangement is such that the cup 11 can be lifted easily by the ring 21, which allows the cup to hang in an exactly vertical position while readings are being taken. The hook 20 may be on the side of the containing vessel 18 in the case of larger containers.

A viscosity measurement is made by withdrawing the cup from the liquid by lifting the handle 15 by the ring 21 and measuring the time which elapses after the withdrawal of the cup 11 from the surface of the liquid 14 until there is a break 5 in the stream of liquid issuing from the orifice 12 of the cup 11. It will be understood that, in using this test method in connection with various liquids varying greatly in viscosity, several viscosity cups may be employed in which the orifices 12 10 vary in size in order to obtain suitable time periods for the emptying of the viscosity cup.

The time required for the viscosity cup to empty to the point where a break in the liquid stream occurs depends, of course, on the viscosity 15 of the liquid, the size of the orifice, and the vertical length of the cup. The friction or viscosity characteristics of a thin plate orifice such as that formed by making an opening in sheet material are much more definite than those of a tube and 20 an orifice may be reproduced more accurately so that more accurate readings of viscosity are obtained than by employing apparatus of the flow type having long tubes. The simplicity of the apparatus also overcomes the difficulties in connection with the proper cleaning of complicated 25 viscosity vessels with irregular surfaces and long tubes, and the fact that the viscosity cup is kept immersed in the liquid makes it possible to maintain the entire viscosimeter uniformly at the temperature of the liquid being studied. 30

The precision of the measurement is facilitated by reason of the fact that there is a sudden break of flow at the end of the period during which the cup empties and the instant at which a break 35 occurs in the flow of liquid at the base of the cup 11 is very definite and can easily be determined whereas, in the ordinary flow type of viscosimeter, it is necessary to measure a predetermined quantity of liquid by observing the exact instant when 40 the surface level of the liquid reaches a given graduate line on a receiving receptacle and this determination is of necessity relatively indefinite.

Although my invention is not limited to any specific dimensions, I have found that satisfactory 45 results may be obtained by employing a viscosity cup made of one-sixteenth inch steel and having a capacity of about forty-five cubic centimeters.

In case it is desired to obtain a temperature-viscosity curve of a liquid, the vessel 18 for the 50 liquid 14 may be placed upon a stove or other source of heat, such as a gas flame 19, and readings, repeated at short intervals, may be taken as the temperature of the liquid rises and again as the temperature cools after the gas flame 19 is 55

shut off. It will be understood, of course, that a suitable thermometer, not shown, is to be immersed in the liquid 14.

In accordance with the provisions of the patent statutes, I have described the principle of operation of my invention together with the apparatus which I now consider to represent the best embodiment thereof but I desire to have it understood that the apparatus shown is only illustrative and that the invention may be carried out by other means.

What I claim as new and desire to secure by Letters Patent in the United States is:

1. A viscosimeter comprising in combination a

bullet-shaped cup having an orifice in the bottom thereof, a handle attached to said cup for suspending it in a liquid, the viscosity of which is to be determined, and a lifting ring movably attached to said handle for providing free vertical 5 suspension of the cup.

2. A viscosimeter comprising in combination, a cup composed of sheet material with a thin plate orifice in the bottom thereof, said cup being adapted to be kept immersed in a liquid, the viscosity of which is to be tested, and means for vertically withdrawing said cup from the liquid to make a viscosity test.

ERWIN A. ZAHN.
